UNITED STATES PATENT OFFICE.

CHARLES ROZELL, OF HUTCHINSON, KANSAS.

DESIGN FOR A CROWN-PIECE ATTACHMENT.

SPECIFICATION forming part of Design No. 30,035, dated January 17, 1899.

Application filed December 20, 1898. Serial No. 699,869. Term of patent 14 years.

To all whom it may concern:

Be it known that I, CHARLES ROZELL, a citizen of the United States, residing at Hutchinson, in the county of Reno and State of Kansas, have invented and produced a new and original Design for a Crown-Piece Attachment for Bridles, of which the following is a specification.

This invention relates to a new and original design for a crown-piece attachment for bridles; and it has for its object to provide a design of this character that shall be both useful and ornamental.

The leading feature of the design resides in an oblong body-plate provided at or near its opposite ends with the oppositely-located upstanding split terminal loops and at a point centrally between its ends with a central upstanding loop arranged in longitudinal alinement with the terminal loops, said body-plate being further provided in advance of the central loop with a forked extension having a pair of spaced parallel folded arms.

While the essential feature of the design resides in the relative arrangement and disposition of the three loops in connection with the forked extension in advance of the central loop, the design embodies a number of minor features, such as the oblong body-plate, having a slight longitudinal curvature, and narrowed neck portions between the central and terminal loops.

Additional minor features of the design are the upstanding terminal loops, being of a rounded inverted-U-shaped form, and the central loop of an angular inverted-U-shaped form, and also in the body-plate being provided within the vertical plane of the several loops and at the bases thereof with rectangular openings, piercing the plate.

It is also a minor feature of the design to have the separate parallel arms of the forked extension folded upon themselves at an intermediate point into an approximate U shape.

In the accompanying drawings, Figure 1 is a perspective view of a crown-piece attachment for bridles embodying the herein-described design. Fig. 2 is a plan view thereof. Fig. 3 is a front elevation. Fig. 4 is a sectional view on the line 4 4 of Fig. 3.

In the accompanying drawings the numeral

1 designates an oblong body-plate having a rectangular outline and also having a slight longitudinal curvature. The said longitudinally-curved oblong body-plate 1 is provided at or near its opposite ends with the oppositely-located upstanding split terminal loops 2 of a rounded inverted-U shape. The said oppositely-located terminal loops 2 are disposed in the same direction and are located in a vertical plane intermediate the longitudinal side edges of the body-plate, and the latter is provided therein, in the plane of the terminal loops 2, with rectangular openings 3, which pierce the plate. The rounded split terminal loops 2, which project above and are arched over the rectangular openings 3 of the body-plate, are provided at one side of their vertical centers with the slits 4 to facilitate the engagement and disengagement of the separate portions of an overcheck-rein with the terminal loops.

At a point centrally between its ends the body-plate 1 is also provided with a rectangular opening 5, piercing the same, and arched over this opening is the central angular inverted-U-shaped loop 6, projected upwardly from the upper side of the body-plate and arranged in longitudinal alinement with the rounded terminal loops 2. Between the central loop 6 and said terminal loops the body-plate is provided with narrowed or contracted neck portions 7.

At one side edge and in advance of the central loop 6 the body-plate 1 is provided with an offstanding forked extension 8, having a pair of spaced parallel arms 9, folded upon themselves into an approximate U shape and providing means for the attachment of a winker-strap buckle to the plate, at one side of the central loop 6 thereof.

What is claimed is—

The design for a crown-piece attachment for bridles, herein shown and described.

In testimony that I claim the foregoing as my own I have hereto affixed my signature in the presence of two witnesses.

CHARLES ROZELL.
